UNITED STATES PATENT OFFICE.

CHRISTIAN F. SANDERS AND JOHN T. SWEARINGEN, OF HEDRICK, IOWA.

THILL-COUPING.

SPECIFICATION forming part of Letters Patent No. 613,426, dated November 1, 1898.

Application filed March 21, 1898. Serial No. 674,673. (No model.)

To all whom it may concern:

Be it known that we, CHRISTIAN F. SANDERS and JOHN T. SWEARINGEN, citizens of the United States, residing at Hedrick, in the county of Keokuk and State of Iowa, have invented a new and useful Thill-Coupling, of which the following is a specification.

The invention relates to improvements in thill-couplings.

10 The object of the present invention is to improve the construction of thill-couplings and to provide a simple, inexpensive, and efficient device capable of preventing noise and rattling and adapted to permit a pair of thills or a pole to be readily attached to or uncoupled from a vehicle.

A further object of the invention is to prevent a thill-iron from becoming accidentally disconnected from the bearings of an axle-clip when a vehicle is passing over a rough road.

20 The invention consists in the construction and novel combination and arrangement of parts, as hereinafter fully described, illustrated in the accompanying drawings, and pointed out in the claims hereto appended.

In the drawings, Figure 1 is a perspective view of a thill-coupling constructed in accordance with this invention. Fig. 2 is a longitudinal sectional view. Fig. 3 is a transverse sectional view. Fig. 4 is a detail perspective view of the thill-iron, the plates which form the flanges being in position. Figs. 5 and 6 are detail perspective views of the plates which form the flanges of the eye of the thill-iron. Fig. 7 is a detail perspective view of the cap or cover of the bearing-box of the axle-clip. Fig. 8 is a longitudinal sectional view illustrating a modification of the invention. Fig. 9 is a detail perspective view of a thill-iron having integral flanges for engaging the bearing-box of the axle-clip. Fig. 10 is a vertical sectional view on line 10-10 of Fig. 3.

45 Like numerals of reference designate corresponding parts in all the figures of the drawings.

1 designates a bearing-box mounted on an axle-clip 2 and adapted to receive the eye or 50 rear end of a thill-iron 3 and provided with a hinged cover 4, adapted to bear on the thill-iron to form an antirattler. The bearing-

box, which is provided at its front with an opening 4^a for the reception of the thill-iron 3 and to permit the same to play vertically 55 incident to horse motion, is provided at opposite sides with grooves 5, adapted to be engaged by flanges of the eye of the thill-iron. The opening 4^a is of less width than the axle-box, and the grooves 5, which receive the flanges, are formed in the bottom and front wall of the bearing-box at opposite sides of the opening 4^a.

The flanges, which are located at the ends of the eye of the thill-iron, are preferably 65 formed by plates 7 and 8, detachably interlocked with the thill-iron; but they may, as illustrated in Figs. 8 and 9, be formed integral with the same. The plates 7 and 8, which are substantially segmental, the flanges 70 being cut away at the top, are provided at their inner faces with lugs 9, which interlock with recesses 10 at the top and bottom of the eye of the thill-iron, and the plate 8 is provided with a pin 11, passing through the eye 75 of the thill-iron. By this construction flanges may be readily provided at the ends of an ordinary thill-iron to enable the improvements to be applied to a vehicle without necessitating any change in the thill-irons except the notches or recesses 10.

The lid 4, which is hinged at one side of the bearing-box, at 12, is provided at its inner face with an enlargement 13 and is secured when closed by a spring-catch 14. The 85 enlargement 13 is provided with curved bearing-faces 15, which when the lid or cover is closed complete the bearing of the bearing-box. The spring-catch consists of a strip of resilient material secured to the outer face 90 of the bearing-box at one end thereof, preferably in a recess, so that its outer face will be flush with the face of the bearing-box, and the upper end of the spring projects above the bearing-box and is coiled or otherwise 95 bent to form a shoulder at its inner side for engaging the free end of the lid or cover.

In order to prevent the thill-iron from being jolted out of the bearing-box when a vehicle is passing over a rut or obstruction, the 100 flanges are provided with lugs 16, extending upward or rearward and adapted to interlock with corresponding recesses 17, arranged at opposite sides of the enlargement 13 of the

lid or cover. The lid or cover is provided at its hinged end with a flange, and the bearing-box has an opening near its upper edge, the connecting portion at the top of the opening being rounded to form a pintle and the flange of the lid or cover being bent around the same to form an eye.

In Figs. 8 and 9 of the accompanying drawings the flanges of the thill-iron are formed integral with the rounded portion 18, which is arranged within the bearing-box, and the thill-iron 19 is provided adjacent to the portion 18 with a projection or lip 19^a, forming a hook and adapted to engage a recess of the 15 enlargement of the lid or cover to prevent the thill-iron from being jolted out of the bearing-box. The integral flanges 21 of the thill-iron 19 interlock with grooves of the bearing-box, similar to the flanges before described.

The invention has the following advantages: The thill-coupling, which is simple and comparatively inexpensive in construction, enables a pair of thills and a pole to be 25 readily coupled to and uncoupled from a vehicle by swinging the thills or poles upward after the lid or cover has been opened; but should the thills swing upward incident to a 30 vehicle passing over a rut or obstruction the thill-iron will interlock with the cover and will be prevented from jolting out of the bearing-box. The lid or cover bears upon the thill-iron and prevents the parts from rattling. The flanges, which interlock with the 35 grooves of the bearing-box, may be formed integral with the thill-iron, or they may be applied to the ordinary thill-iron, which is provided with an eye.

Changes in the form, proportion, and minor 40 details of construction may be resorted to without departing from the spirit or sacrificing any of the advantages of this invention.

What we claim is—

1. In a thill-coupling, the combination of 45 a bearing-box having an opening at its front and provided at opposite sides with bearings having grooves, a thill-iron arranged in the opening of the bearing-box and having a rounded portion journaled in the said bearings, and flanges arranged at the ends of the rounded portion and interlocked with the 50 said grooves, substantially as described.

2. In a thill-coupling, the combination of 55 a bearing-box having grooves at its ends, a thill-iron having an eye arranged in the bearing-box, and plates detachably interlocked with the ends of the eye and engaging the grooves of the bearing-box, substantially as described.

3. In a thill-coupling, the combination of

a bearing-box having grooves, a thill-iron journaled in the bearing-box and provided at the ends of its eye with recesses, and plates arranged at the ends of the eye, projecting beyond the same to form flanges and provided with lugs interlocked with the recesses, substantially as described.

4. In a thill-coupling, the combination of 65 a bearing-box having an opening, a lid or cover hinged at its rear edge to the bearing-box, and a thill-iron journaled in and interlocked with the bearing-box and adapted to be removed therefrom when swung upward to a vertical position, said thill-iron being provided with means for engaging the front 75 edge of the lid or cover when it is swung upward, whereby it is prevented from being jolted out of the bearing-box, substantially as described.

5. In a thill-coupling, the combination of 80 a bearing-box, a lid hinged at its rear edge to the bearing-box and provided at its front edge with a recess, and a thill-iron journaled in the bearing-box and provided with a hook-shaped projection arranged to engage the recess when the thill-iron swings upward, substantially as described.

6. In a thill-coupling, the combination of 85 a bearing-box having grooves, a lid provided with opposite recesses, a thill-iron having an eye arranged within the bearing-box, plates interlocked with the eye of the thill-iron, forming flanges and provided with lugs to engage the said recesses, substantially as described.

7. In a thill-coupling, the combination of 90 a bearing-box having grooves, a lid having recesses, and a thill journaled in the bearing-box and provided at the ends of its eye portion with flanges having hook-shaped lugs 100 or projections to engage the said recesses, substantially as described.

8. In a thill-coupling, the combination of 105 a bearing-box provided at its front with an opening and having grooves at opposite sides thereof, a thill-iron journaled in the bearing-box and provided at the ends of its eye portion with flanges to interlock with the said grooves, and a lid or cover provided with an 110 enlargement having bearing-faces and engaging the thill-iron to prevent the same from rattling, substantially as described.

In testimony that we claim the foregoing as our own we have hereto affixed our signatures in the presence of two witnesses.

CHRISTIAN F. SANDERS.
JOHN T. SWEARINGEN.
